MULTIPLE-EFFECT FUSE FOR ARTILLERY-PROJECTILES.

1,237,816.

Specification of Letters Patent. Patented Aug. 21, 1917.

Application filed May 5, 1915. Serial No. 25,969.

To all whom it may concern:

Be it known that I, EMILE RIMAILHO, a citizen of the French Republic, and residing in Paris, France, 98 Rue de la Victoire, consulting engineer, have invented certain new and useful Improvements in and Relating to Multiple-Effect Fuses for Artillery-Projectiles, of which the following is a complete specification.

10 This invention relates to a multiple effect fuse for artillery projectiles.

When the complete fuse is mounted on a shell of the universal type, the results described hereinafter will be obtained, it being 15 taken into account that shells of the said type contain a charge of powder for the projection of bullets and also an explosive charge.

The setting of the fuse may be adjusted 20 by hand in the constructional form contemplated in two different ways. To this end it is mounted on the fuse carrier through the medium of a spring controlled ring; drawing the fuse in an upward direction so as to 25 compress the spring, the locks are disengaged, rotation is effected and the locks retracted by the spring into the notches of the new position. In the first position, the firing of the composition of the time fuse produced by the operation of a special concussion device described hereinafter, is directed 30 toward a tube communicating with the rear charge; in the second position the fire is directed through another channel toward the 35 axis of the fuse in order to detonate the explosive charge of the projectile.

In this manner two effects are obtained; the fusing effect for shrapnel and the explosive fusing effect, but in both cases the 40 fuse is arranged in such a manner that the shell can operate by percussion on hitting the object aimed at either through the intermediary of an ignition retarding device or 45 instantaneously by impact. Finally a fifth effect is still possible. When the fuse is mounted with a view to the production of shrapnel ignition, the forward part of the shell containing the explosive may either 50 operate ineffectively on impact or fail to operate at all and in order to avoid these drawbacks provisions are made for insuring in every case the ignition of the explosive through the medium of the retarding charge or at the moment the shrapnel bursts.

55 The instantaneous or retarded percussive

effects as aforesaid, are obtained by the provision of a central part the whole of which constitutes a double acting percussive detonating fuse merely screwed into the body of the time fuse, but which may be fixed directly in the nose of the explosive shell when it is not desired to operate with a time fuse.

The provision of a double acting percussive detonating fuse has for its object to combine a percussive system provided with a retarding charge, with the impact detonating means, instantaneousness of the operation implying the elimination of the delay inherent to percussive devices based upon the utilization of the longitudinal inertia, the instantaneously operating system being, however, usable without the adjunction of the percussive system with the retarding charge.

One constructional form of the invention is illustrated, by way of example, in the accompanying drawings.

Figure 1 illustrates the complete multiple effect fuse,

Fig. 2 illustrates the time fuse alone 80 mounted on a projectile,

Figs. 3 and 4 illustrate respectively the percussive system detached from the time fuse in the inoperative position before the projectile is fired, and in the operative position of the instantaneous percussive system.

Fig. 5 shows a treble acting fuse obtained by the elimination of the spring controlled ring,

Fig. 6 is a developed view of the concussive system which ignites the powder ring of the regulators on firing the projectile,

Fig. 7 is a section through the centrifugal pellets of the instantaneous percussive system.

The fuse illustrated in Fig. 1, is provided at its base with a screw-threaded ring 1 constantly retained in the recess 2 formed in the body of the fuse, by the spring 3 which bears on the flange 4. The upper cylindrical part of the ring which penetrates the recess 2, is provided with notches for facilitating the screwing in position of the same.

In order to place the fuse and its ring in position on the shell, the screw-threads of the ring 1 are caused in the first place by hand, to engage the corresponding screw threads formed in the fuse carrier, the fuse is raised by compressing the spring 3 by the flange 4, this raising movement uncovering

the screwing notches of the ring and by means of a key, the whole thing is screwed home completely. The screw-threaded ring is subsequently locked in place by means of a lock stud 5.

5 The fuse carrier is formed upon its upper edge with rectangular notches 6 intended to receive the pins 7 projecting underneath the plate of the fuse body. When the screw-threaded ring 1 is screwed home, it is sufficient to turn the fuse by hand in order to bring the pins 7 in a position facing the notches 6; under the pressure of the spring 3 the pins enter the notches and the fuse is locked in position.

10 In the thickness of the body of the fuse itself and starting from the upper surface of the plate serving as a support for the regulators, a fire transmitting channel 8 is formed which opens on the lower surface of the body 9 of the fuse at a point set-off from the longitudinal axis of the projectile. The channel 8 may be brought, by rotating the fuse, into the position illustrated in Fig. 1, 15 in communication with the conduit 55 transmitting the fire to the rear charge, or in communication with the conduit 56 diametrically opposite, leading to the detonator 22 through the conduits 53.

15 The two regulators 10, 11, are mounted in known manner on the plate of the body of the fuse, but the upper fixed regulator 11 has this peculiarity that it carries the members of the concussive system intended to produce the ignition of the fuse cord on firing the shot, as shown in Fig. 6. To this end, the circular groove 12 is formed on the upper face of the regulator and serves as a seat for a blade spring 13 carrying at its 20 end, a percussion pin 14; underneath the latter a primer 15 is provided, communicating through the conduit 16 with the fuse cord 17 (Fig. 6).

25 Finally the body of the fuse is formed in its center and throughout its length, with a cylindrical aperture 18, (Fig. 2) intended to receive the whole of the detonator and the percussive members.

30 The whole of the detonator and of the percussive system constitutes a double acting percussive detonating fuse, illustrated in Figs. 3 and 4, detached from the time fuse.

35 A sleeve 19 hollowed out cylindrically, is closed at its lower part by a plug-like member 20 upon which the casing 21 is screwed, containing the detonator 22; a central cylindrical body 23 constituted by two parts assembled by a driven fit at 24, is formed internally with a chamber 25 which serves for 40 housing the percussive system of known disposition.

45 The safety device of this apparatus is constituted by centrifugal masses 26 arresting the igniting members in the inoperative position as shown in Fig. 3, by means of a

safety ring 27 and a central tube 28 maintaining the centrifugal masses 26 at the bottom of a conical cup 29. The percussion pin 30 has this peculiarity that it is placed freely in its seat and has its bottom flange bearing 70 on the spring 54.

50 The rear portion of the central body is formed with a cylindrical boss 31 projecting in a downward direction, in which a cylindrical member 32 containing the retarding 75 device is screwed, in which there is located a small amount of compressed powder 33; the said member extends through the plug 20 and extends into the casing of the detonator 22 and is terminated by a percussion pin 34 80 formed at 35 with two orifices intended for the passage of the gas produced by the ignition of the powder charge 33.

85 The upper face of the plug 20 is formed with a seat for the centrifugal masses 36 serving as stops for the rear of the central body 23. When these masses 36 are in place in their seats the percussion pin 34 of the central body 23 is maintained at a suitable distance above the detonator 22.

90 The cylindrical recess of the sleeve 19 in which the central body is located, is closed at the forward end by the cup-shaped member 44 retained in place by means of a screw-threaded ring 43 screwed on to the sleeve 19. 95

95 The forward edge of the central body 23 carries a rod 37 which traverses the cup-shaped member 44 centrally. Upon this rod there are provided:—a square member 40 engaging an aperture of similar cross-section 100 formed in the said cup-shaped member and a head piece 38 screwed or riveted on the forward end.

105 The square member 40 insures the operation of the central body during the rotary 105 movement. The head 38 fixes on the rod 37 the sleeve 47 the flexible hooks 42 of which support at the rear a pellet 46. So long as the pellet 46 is supported by the hooks 42 it remains longitudinally integral with the central body 23.

110 A spring 45 resting on the cup-shaped member 44, pushes constantly in a forward direction the pellet 46 and therewith the whole of the central body. This forward 115 stroke is limited by an inner projection formed on the screw-threaded ring 43. In this position, a suitable clearance 39 is reserved between the cup-shaped member 44 and the forward edge of the central body 23, 120 said clearance permitting subsequently of the disengagement of the pellets 36 when the body 23 will be able to effect a stroke in a forward direction. The screw-threaded ring 43 exceeds the forward edge of the 125 sleeve 19 and the apparent height of the screw-thread is intended to receive a nut 48 abutting against the forward edge of the said sleeve 19. When the nut or cap 48 is in place, the central body 23 being locked 130

through the medium of the rod 37, cannot effect any movement in a forward direction and the pellets 36 remain imprisoned in their recesses; the projectiles which will be fired 5 will act (the cap 48 being in place) in a percussive manner but with a delay; under these conditions the primer 49 being locked by the pellets 26, is disengaged when the projectile rotates under the effect of the central 10 centrifugal force which separates the pellets 26. Owing to the shock which is produced when the projectile strikes an object, this primer 49 strikes its percussion pin 30 and the fire is propagated to the detonator 22 15 through the medium of the retarding powder charge 33.

When on the contrary, the cap 48 before the introduction of the projectile into the gun, is removed, the explosion takes place 20 instantaneously on the striking of an object by the projectile, in the following manner:—

On firing, the pellet 46 acts by its inertia in known manner and the expansion of the 25 spring 45 which takes place after having left the barrel of the gun, has for its effect to push the central body 23 in a forward direction through the medium of the hooks 42 the ends of which are located in the 30 groove 41. The forward movement of the central body 23 is limited by the cup-shaped member 44 and the tip 34 of the lower percussion pin moves away from the detonator 22 to the extent of a few millimeters.

In this position the pellets 36 can, under 35 the effect of the retardation, advance beyond their seat and move away under the effect of the centrifugal force, the projectile having begun its movement of rotation. Owing 40 to this double movement, they take place in the annular space 51 provided around the boss 31.

On impact, the head 38 being the first 45 point of the shell which strikes the obstacle, the whole of the central body 23 is forced inwardly like a nail into the body of the fuse producing the explosion of the detonator 22 by the point 34 as soon as the projectile has traveled a few millimeters after 50 the shock.

The fifth effect indicated above by means 55 of which, when the projectile operates as shrapnel the fire is communicated to the explosive charge through the medium of the retarding charge 33, is obtained by the special disposition of the upper percussion pin 30, which as shown in Figs. 1, 3 and 4 instead of being fixed to the central body 23, is maintained by a spring 54 pushing the 60 same in a forward direction and rests in a rearward direction on a safety tube 28 of known disposition. When shooting with the percussive mechanism operative, at the moment the projectile strikes its target and a 65 shock takes place, everything is performed

as if the percussion pin 30 had been fixed to the central body 23 because its inertia applies it on to its base; when the shell operates as a shrapnel, on the contrary, the head of the projectile receives an extra impulse 70 in a forward direction owing to the explosion, the percussion pin 30 compresses its spring 54 and strikes the primer 49; the effect is then transmitted to the detonator 22 through the retarding charge 33. 75

When in the general device illustrated in Fig. 1, the setting ring 1 is eliminated, the device illustrated in Fig. 5 is obtained in which the body of the fuse itself is formed with the screw-thread which connects the 80 same to the fuse carrier. The fuse can no longer be set: one of the two effects of the fuse is lost. This device therefore can provide a fuse having three effects for explosive shells. The fire transmitting channel 85 communicates directly with the detonator through the medium of the powder chamber 52 and the conduits 53 formed in the member 20. The shrapnel effect existing no longer, the 90 percussion pin of the percussive system comprising the retarding device, is rendered integral with the central body 23 as clearly illustrated in Fig. 5.

Should it be desired to mount a time fuse on the shrapnel and should it be desired to 95 preserve only the time effect and the instantaneous percussive effect, it is sufficient to provide in the recess 18 of the time fuse, a simplified detonator having only the provisions described above referring to instantaneous operation, excluding the devices for 100 operation of the central percussion pin acting on the retarding charge.

What I claim is:—

1. In a multiple fuse for projectiles, a 105 fuse carrier having oppositely arranged passages, one of which communicates with a passage leading to the rear charge of the projectile, a fuse body adjustably mounted on the carrier and having a fire transmitting passage adapted to register with either of the passages of the carrier, a member in the fuse body and extending into the fuse carrier, said member carrying a detonator and having a passage communicating with 110 the other passage of the carrier.

2. In a multiple fuse for projectiles, a 115 fuse carrier having notches, a fuse body mounted to turn on the fuse carrier and provided with projections engaging the notches 120 of the carrier, and means for locking the projections in the notches.

3. In a multiple fuse for projectiles, a 125 fuse carrier having notches, a fuse body mounted to turn on the carrier and having projections engaging the notches, and a spring for permitting the free turning of the body and for holding the projections in the notches.

4. In a multiple fuse for projectiles, a 130

fuse body, two regulator rings mounted on the body one above the other, the lower one carrying a fuse, the upper ring having a groove and a passage leading from the groove to the fuse and provided with a primer and a spring actuated percussion pin in said groove.

5. In a multiple fuse for projectiles, a sleeve having a detonator at one end, a longitudinally movable core in the sleeve, said core carrying a primer and having a passage leading from the primer and in communication with the detonator of the sleeve, means for locking the core from movement, 10 and a spring pressed firing pin in the core.

6. In a multiple fuse, for projectiles, a sleeve carrying a detonator at one end, a longitudinally movable core in the sleeve and having a chamber, said core carrying a primer and having a passage leading from the primer and in communication with the detonator of the sleeve, a tube mounted in the chamber of the core, and having one end reduced, a headed firing pin mounted 20 in the reduced end of the tube with its head engaging the end of the chamber, and a spring surrounding the reduced end of said tube.

7. In a multiple fuse for projectiles, a sleeve carrying a detonator at one end, a longitudinally movable core in the sleeve and carrying a firing pin at one end, said core having a chamber intermediate of its ends, and a seat in said chamber, centrifugally operated members in the chamber and adapted to rest on the seat and in engagement with the core, and means for retaining the same members on the seat.

8. In a multiple fuse for projectiles, a sleeve carrying a detonator at one end, a longitudinally movable core in the sleeve and carrying a firing pin at one end, said core having a chamber intermediate of its

ends and a seat in said chamber, centrifugally operated members in the chamber 45 and adapted to rest on the seat and in engagement with the core, and a spring pressed tube in the core and engaging the said members to hold them on the seat.

9. In a multiple fuse for projectiles, a sleeve having a seat in its lower end, a detonator casing secured to the said lower end of the sleeve, a longitudinally movable core in the sleeve and having a chamber intermediate of its ends and a seat in the chamber, the lower end of the core being reduced, a member secured to the reduced end and extending through the sleeve into the detonator casing and carrying a firing pin, centrifugally operated members in the chamber 60 and adapted to rest on the said seat in engagement with the core, means for holding the members on the seat, and centrifugally operated members adapted to rest in the seat in the end of the sleeve. 65

10. In a multiple fuse for projectiles, a sleeve carrying a detonator at one end, and having an apertured partition at its other end, a longitudinally movable core in the sleeve and having one end reduced and carrying a firing pin at its other end, a member surrounding the reduced end of the core, means including a head for connecting the said member with the reduced end of the core, a spring between the said member and the partition of the sleeve, movable and centrifugally operated members for controlling the movement of the core, and a cap over said head. 70

In testimony whereof I have hereunto set 80 my hand at St. Etienne, France, this third day of April, 1915.

EMILE RIMAILHO.

In the presence of two witnesses:

P. VOPILL,
DAVIS B. LEVIS.
